WHEELED VEHICLE FRAME

Garry W. Ruby, 3635 Belle,
San Bernardino, Calif. 92404

Filed Apr. 7, 1969, Ser. No. 16,594

Term of patent 14 years

Int. Cl. D12—11

U.S. Cl. D34—15

FIG. 1.

FIG. 2.

FIG. 3.

FIG. 4.

FIG. 5.

FIG. 1 is a side elevational view of a wheeled vehicle frame showing my new design;

FIG. 2 is a top plan view of the same;

FIG. 3 is a bottom plan view thereof;

FIG. 4 is a front end elevational view; and

FIG. 5 is a rear end elevational view thereof.

The elements shown in broken lines are included for illustrative purposes only.

I claim:

The ornamental design for a wheeled vehicle frame, as shown and described.
